CLAIM

We claim, the ornamental design for a user-wearable holder for medical device, as shown and described.

DESCRIPTION

FIG. 1 is a perspective view of a user-wearable holder for medical device.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an additional perspective view thereof; and,

FIG. 9 is a further perspective view thereof.

Items shown in broken lines depict environment and portions of the medical device that form no part of the claimed invention.

1 Claim, 7 Drawing Sheets
